UNITED STATES PATENT OFFICE.

WILLIAM M. BOWES, OF NEW YORK, N. Y.

DESIGN FOR A HANDLE OF SCISSORS-BLADES.

43,265.

Specification for Design.

Patented Nov. 26, 1912.

Application filed July 8, 1912. Serial No. 708,368. Term of patent 7 years.

To all whom it may concern:

Be it known that I, WILLIAM M. BOWES, a citizen of the United States, residing in the city of New York, borough of Brooklyn, in the county of Kings and State of New York, have invented a new, original, and ornamental Design for the Handle of a Scissors-Blade, of which the following is a specification, reference being had to the accompanying drawing, forming part thereof.

The figure is a plan view of a scissors blade handle showing my design.

I claim:

The ornamental design for a handle of a scissors blade as shown.

WILLIAM M. BOWES.

Witnesses:

THEO. G. HOSTER,
PHILIP D. ROLLHAUS.
